UNITED STATES PATENT OFFICE.

AUSTIN D. HOFFMAN, OF CHICAGO, ILLINOIS, ASSIGNOR TO THE NATIONAL FEATHER DUSTER COMPANY, OF SAME PLACE.

FEATHER SPLITTING AND GRINDING MACHINE.

SPECIFICATION forming part of Letters Patent No. 279,386, dated June 12, 1883.

Application filed December 15, 1882. (No model.)

To all whom it may concern:

Be it known that I, AUSTIN D. HOFFMAN, of Chicago, in the county of Cook and State of Illinois, have invented certain new and useful 5 Improvements in Machines for Splitting Feathers and in Combined Machines for Splitting and Grinding Feathers; and I do hereby declare that the following is a full, clear, and exact description thereof, reference being had to the accompanying drawings, and to the letters of reference marked thereon, which form a part of this specification.

This invention relates to improvements in devices for splitting feathers in the manufacture of feather-dusters.

It also relates to the combination of a feather-splitting machine with mechanism for grinding out the pith of the feather-shaft after the splitting has been accomplished. The mechanism for splitting the feather-shaft is of that kind which embraces a stationary knife and feeding devices by which the feather is carried through the machine in such relation to the knife as to cause the latter to cut away the 25 inner portion of the shaft close to the plume.

The improvements herein described and claimed, and relating especially to the splitting mechanism, have for their object to provide such a construction in this class of machines as will adapt them to work more perfectly, reliably, and expeditiously. The grinding mechanism is in itself generally of the ordinary construction, consisting of an abrading or grinding-roller, arranged in opposition to a supporting-roller, and combined with feeding-rollers, which control the movement of the feather in its passage beneath the grinding-surface.

The improvements relating to the combination of the splitting with the grinding mechanism have for their object to direct the feathers successively to the grinding devices after being split and in proper position to enter the feed-rollers, so that the exposed pith or cut 45 surface of the shaft will be subject to the grinding-surface, while the uncut surface of the shaft will be brought to bear upon the supporting-roller of the grinding mechanism.

The invention consists in the several matters hereinafter fully described, and pointed out in the claims.

In the accompanying drawings, Figure 1 is

a side elevation of a machine embracing both a splitting and a grinding apparatus. Fig. 2 is a vertical section through xx of Figs. 3 and 55 4. Fig. 3 is a top or plan view of the machine. Fig. 4 is a vertical section through xx of Fig. 2.

A^0 is a bench, base, or frame, on which the combined machine rests. A A are the parallel end plates or uprights of the frame of 60 that portion of the machine which contains the grinding mechanism. A' are the parallel end plates or uprights of that portion of the machine which contains the splitting mechanism. Said end plates are connected by suitable cross-pieces to give rigidity to the frame, and the various rollers are mounted on parallel axes between their planes.

The general arrangement of the several operating devices will be best seen by reference to 70 the sectional view, Fig. 2, in which B is the shaft of the grinding-drum B' , and C' is a roller opposed thereto, being vertically adjustable by means of sliding journal-boxes, which rest on adjusting-screws c^4 . C and C' are the shafts of 75 the feed-rolls C and C' , which carry the feathers inward to the grinding-drum, the upper of said shafts being vertically adjustable by being mounted in the pivoted arms c^5 , controlled by adjusting-screws c^6 , one at each end of the 80 roller.

H is the splitting-knife, secured in a horizontal position to the uprights A' . Beneath the edge of said knife is situated a conical or tapering friction-roller, I , intended to support 85 the feather in proper position to be suitably split. This conical roller is mounted by its end spindles in the upper ends of the arms I' , which are pivoted at their lower ends to the levers I'' , in turn pivoted to the frame at i^2 , 90 and adjustable at their outer ends by means of the thumb-screws i , arranged to bear on a subjacent stationary part, a , of the machine. Between its ends each of the arms I' is also pivotally connected with an arm, I^3 , which is 95 provided at its outer end with a set-screw, I^4 , entering the arm through a slot, i^4 , in the frame, and by which the arm is held fixed in any desired position. By means of the above connections of the roller I , said roller may be 100 adjusted in any direction, so as to be brought exactly beneath the knife-edge, however much said edge may be ground away from use, and so as to vary the depth of cut as may be de-

sired—that is to say, the roller I is vertically adjustable by means of the lever I² and screw i, and is laterally adjustable by means of the arms I³ and set-screw I⁴.

5 D and D' are the lower shafts of two pairs of feed-rollers mounted by suitable spindles in the plates A', and arranged one in front and the other at the rear of the knife H. The shafts F and F' of the opposing upper feed-rollers are mounted in yokes F², one yoke above each end frame-plate A'. Said yokes are rigidly connected with each other by the central rod, h², and are held in position by pins F¹, which rise from projections a¹ of the frame 10 A', and pass through apertures in the feet f² of said yokes. Automatic vertical adjustment and variable pressure of the rollers mounted in said yokes is obtained by means of the nuts F⁴, threaded on the upper ends of 15 the pins F¹, and the coiled expanding springs f³, interposed between said nuts and the feet f² of the yokes. A spring-presser, h, is arranged over and extending a little in front of the knife-edge, being secured at its ends to 20 the yokes by spring-arms h'. This presser serves to bear the feather downward upon the 25 conical roller.

G is a feed-table arranged in position to direct the feather between the front feed-rollers,

30 D³ and F⁵; and, if desired, a similar table may be placed beneath the knife to assist in directing the end of the feather-shaft between the rear feed-rollers, though in practice this is not found necessary. Both pairs of feed-rollers— 35 that is to say, the pair D³ F⁵ and the pair D⁴ F⁶ are of course driven to carry the feather rearward against and beyond the knife H. The rear pair of these rollers is also caused to run at a little higher speed than the front 40 pair, for the purpose of drawing the feather taut and preventing it from buckling or doubling up in front of the knife.

J is a smooth-surfaced sheet-metal plate bent and arranged in the position shown, intended to support the outer or unplumed end 45 of the feather-shaft and to direct the feather tip first to the feed-rollers C² C³ of the grinding mechanism.

L is a plate against which the tip of the 50 feather falls in its descent, after passing the splitting mechanism, and which co-operates with the plate J in directing the feather to the grinding devices.

It has been above stated that the supporting- 55 roller I is conical. This feature is best shown in Fig. 4. The object of this construction of the roller I is to enable the machine to split the tapering shaft of the feather about centrally, or close to the plume, throughout its length or 60 throughout the greater part of its length. This is accomplished by inserting the feather obliquely, as indicated in Fig. 3. The cylinder or base of the feather-shaft is inserted foremost and over the smaller end of the roller I, and as the 65 feather advances the thinner parts of the shaft pass over the larger parts of said roller. Experience readily teaches the operator to so di-

rect the feather that the latter will be cut or split in a line close and parallel to the plume throughout its length. 70

The combined splitting and grinding machines as here organized are driven as follows, and as will be best seen by reference to Fig. 1: On the extended shaft B of the grinding-drum are located a fixed and a loose pulley, B', receiving the driving-belt T. A pinion, b, also on the shaft B, meshes with a spur-gear wheel, c, on the shaft C of the lower feed-roller, C², and a pinion, c², thereon drives the opposing or upper feed-roller, C³, by a pinion, c³. On 80 the shaft C is also fixed a belt-pulley which connects by a cross-belt, T', with the pulley D² on the shaft D' of the splitting mechanism. Each pair of feed-rollers of the splitting mechanism is provided with intermeshing, deep cut pinions d f and d' f', and an idle-gear, E, communicates motion from the pinion d' on the shaft D' to the pinion d of the front pair of feed-rollers. A less number of teeth on the pinions d and f' than are present on the pinions d and f produce the higher speed of the former, above referred to. The speeds of the splitting and grinding mechanisms are suitably timed to co-operate, in order that the latter may dispose of the feathers as fast as delivered thereto from the splitter. 90

In the operation of the machine, the base of the shaft is forced rearward and upward against or over the top of the plate J, and when the tip emerges from the rearmost feed-rollers the feather falls tip downward and with its cut surface upward upon the plate J. The feather slides downward in this position on said plate, and is caught by the rollers C² and C³ and carried forward between the grinding-drum B² and its opposing rollers C⁴, and the exposed pith is removed as it advances beneath the grinding-drum. The feather finally emerges and is conducted between the plates M and M' to a receptacle provided to receive it. 105

I am aware that a grinding-roller and an opposing roller have been arranged with a space of unequal width between them, for the purpose of removing a portion of the shaft of the feather and the pith at the same time. By my 115 machine, as before described, the feather is first split in a line parallel with the plume, in which operation a tapered shaving is taken off, and the pith is then removed by the grinding-roller. A much more perfect result is thereby 120 obtained than by the device first mentioned, for the reason that the previously-split shaft of the feather is flattened while in contact with the grinding-roller, the surface of which is parallel with its opposing roller, so that said roller 125 acts with equal effect in removing the pith throughout the entire length of the shaft.

I make no claim, broadly, to feeding-rollers located at the rear of the knife, as these, as well as front rollers, are very old in splitting 130 and kindred machines. Nor do I claim, broadly, a supporting-roller beneath the knife-edge, as this, too, is very old; but

I claim as my invention—

1. In a machine for splitting feathers, the combination, with a stationary knife and with a roller for supporting the feathers at the knife-edge, of two pairs of feed-rollers, located one pair in front and the other pair at the rear of the knife, and means for driving both pairs, the rear rollers being driven at a higher speed than the front ones, substantially as described. 5
2. In a feather-splitting machine, the combination, with a grinding-roller, of a knife and a conical supporting-roller arranged to afford a space of unequal width between said roller and the knife-edge, substantially as described. 10
3. The combination, with the knife and conical roller, arranged as described, of a yielding presser, h , substantially as described. 15
4. The combination, with the knife and roller for supporting the feather at the knife-edge, of arms I' , carrying the roller, levers I^2 , for vertically adjusting the roller, and means for laterally adjusting the roller, substantially as described. 20
5. The combination, with the knife and roller for supporting the feather at the knife-edge, of arms I' , carrying the roller, arms I^3 , pivoted thereto, and set-screws I^4 , arranged and operating substantially as described. 25
6. The combination, with the stationary feed-
ing-rollers D^2 and D^4 , of automatically-adjustable yokes F^2 and upper feed-rollers, F^5 F^6 , 30 mounted in said yokes, substantially as described.
7. In combination with the stationary feed-rollers, the yokes F^2 , the feed-rollers mounted in said yokes, yielding presser devices for bearing the yokes downward, and means for adjusting the tension of the presser devices, substantially as described. 35
8. The combination, with the splitting and grinding mechanism, arranged, the former above the latter, as shown, of the plate J , for guiding the split feathers to the grinding mechanism, substantially as described. 40
9. The combination, with the splitting and grinding mechanism, arranged as shown, of the curved plate J and the plate L , for guiding the split feathers to the grinding mechanism, substantially as described. 45

In testimony that I claim the foregoing as my invention I affix my signature in presence of two witnesses.

AUSTIN D. HOFFMAN.
